UNITED STATES PATENT OFFICE.

WILLIAM FREDERICK SCHULTHEISS, OF SAN DIEGO, CALIFORNIA.

ADJUSTABLE METAL BASIN-PLUG.

SPECIFICATION forming part of Letters Patent No. 732,452, dated June 30, 1903.

Application filed February 12, 1902. Serial No. 93,771. (No model.)

To all whom it may concern:

Be it known that I, WILLIAM FREDERICK SCHULTHEISS, a citizen of the United States, residing at San Diego, in the county of San Diego, State of California, have invented a new and useful Adjustable Metal Basin-Plug, of which the following is a specification, reference being had to the accompanying drawings.

10 My invention relates to improvements in metal basin-plugs; and the objects of my improvements are to provide a convenient and thorough method of cleaning and removing sediment and accumulations from the outlet of the basin, which I accomplish by means of a removable and adjustable combination strainer and overflow cut-off, and to provide a safe and convenient method of making water-tight connection between the plug and 15 the basin, which I accomplish by making the basin-plug in two sections and by means of a concave lock-nut.

20 In the drawings, Figure 1 is an elevation showing in section the entire plug and a portion of the basin. Fig. 2 is a view of the combination strainer and overflow cut-off as it appears when removed from the basin-plug, and Fig. 3 is an elevation showing in section the upper portion of the basin-plug with the 25 strainer and overflow cut-off removed.

30 Similar letters refer to similar parts throughout the several views.

35 My adjustable basin-plug is made up of two principal parts A and B, these being connected by means of a heavy screw-thread *a* and being adapted to be inserted from opposite directions through the discharge-opening in the basin *H*. On the upper portion of part B is a concave lock-nut *b*, by means of which 40 a thoroughly water-tight connection is made with the basin. This nut being concave has a tendency to draw the rubber gasket *c*, Fig. 1, firmly against the basin-plug, thus preventing any leakage, whereas a flat-surfaced 45 nut almost invariably causes the gasket to spread away from the plug, making it difficult to effect a water-tight joint. For this reason I prefer to use a concaved nut; but it will be obvious that a flat-surfaced nut 50 may be used, if desired, without departing from the principle of my invention.

Having the basin-plug in two parts A and

B and made up with a lock-nut *b*, it becomes possible to use the plug in connection with either a lead trap or a brass trap, and it also 55 does away with the strain on the basin, which is invariable when an old-style plug is being made up, and all danger of cracking the basin or of twisting the strainer in the plug is eliminated.

60 In making the connection with my plug the part B is first connected with the trap, then the basin is allowed to rest on the lock-nut, and then the part A is connected to the part B from the top by the thread *a*. All that 65 then remains to be done is to make the connection tight by screwing up the nut *b*. As the part B is already attached to the trap, thus making it impossible for the plug to twist, it is evident that all strain on the basin is eliminated. In making a connection with an old-style plug the connection is first made with the basin, the connection with the lead trap then being made by a union-joint. In making this union-joint a considerable strain is 70 necessarily thrown on the part of the plug which is connected with the basin, the basin being often cracked in the operation. In attempting to relieve the basin of this strain it is not unusual for a file or other similar article to be inserted in the cross-pieces which 75 form the strainer of the plug, with the common result that the cross-pieces are twisted, rendering them useless as a strainer. Even 80 in cases where the external clamp-nut feature 85 of my invention described above is not employed I am nevertheless able by means of another feature of my invention to avoid injury to the strainer despite the fact that a tool has to be inserted to relieve the basin of 90 the strain. I accomplish this by the use of the removable combination strainer and overflow cut-off hereinafter described, and in cases where an old-style part B is employed unprovided with my lock-nut *b* I avoid strain 95 upon the basin by removing the strainer-tube when setting up the basin, thus enabling me to insert a plug of wood into the basin-plug far enough to get a purchase sufficient to make 100 the joint tight, after which the strainer may be replaced.

The removable and adjustable combination strainer and overflow cut-off, Fig. 2, is in the form of a tube, which fits into the upper part

the upper shoulder d of the basin-plug and rests on the shoulder d , Fig. 1, and may be made tight by a ground glass joint. Within the tube is the strainer e' , (shown clearly in Fig. 2,) while through the side of the tube is cut a hole e , of suitable size, so situated as to register with the opening f , through which water from the overflow-pipe G enters through the upper portion of the plug A to the interior of the waste-pipe B . This strainer and overflow cut-off can be easily removed from the basin-plug with the fingers, thus providing an easy and satisfactory means of removing ordinary obstructions from the plug or pipe without the assistance of a plumber and doing away with the necessity of gouging the same down and eventually filling the pipe, as is very often the case when a non-removable strainer is used. My combination strainer and overflow cut-off can also be easily adjusted with the fingers, so as to close the long slot f , through which the water which has passed through the overflow-holes g' of the basin enters the waste-pipe, thus cutting off back pressure, which would otherwise result through the overflow-pipe when the waste-pipe is being cleared by means of a force-pump or other pressure appliance. This is accomplished by simply turning the strainer and overflow cut-off one-fourth around, so that the slot f is closed, as shown in Fig. 1, and this not only permits the use of a greater pressure in clearing the waste-pipe and prevents any of the foul and greasy sediment that accumulates in the waste-pipe from being forced into the overflow-passage G of the basin, from which place it cannot be thoroughly removed, but also makes it entirely practicable for one man to attend to the matter. Under the present method of placing the hands over the overflow-inlet g' near the top of the basin in order to obtain a pressure made necessary by the absence of my adjustable overflow cut-off not only is it difficult to obtain much pressure, but the services of two men are necessary.

I claim—

1. In combination with a basin having a discharge-opening, a basin-plug provided with

a flange and adapted to be inserted in the opening from the basin side, a tube adapted to be inserted in the opening from the opposite side and to engage with the plug, and a clamp-nut adjustable in position upon the tube toward and from the flange of the plug to clamp the basin therebetween. 55

2. In combination with a basin having a discharge-opening, two tubes, adapted to be inserted in the opening from opposite sides thereof and to engage each other therein, and two flanges, one on each tube, arranged on opposite sides of the basin, one of the flanges being adjustable in position on its tube toward and from the other flange and arranged to clamp the basin therebetween. 60

3. The combination with a basin having a discharge-opening, a basin-plug therein, and an overflow-passage from the basin leading thereto, of an adjustable plug fitting within the basin-plug, and adapted to close the overflow-passage, said inner plug having an opening in its side whereby by rotation of the plug the overflow-passage may be opened. 70

4. The combination with a basin having a discharge-opening, a basin-plug therein and an overflow-passage from the basin leading thereto, of a removable plug fitting within the basin-plug, said removable plug being provided with a strainer and having walls adapted to close the overflow-passage and having at one side an opening therethrough 80 whereby, by rotating the removable plug, the overflow-passage may be opened. 75

5. As a new article of manufacture a tubular plug adapted to fit rotatably into the discharge-pipe of a basin, said plug being provided with a strainer and having its tubular portion long enough to close the outlet of an overflow-passage from the basin into the discharge-pipe and having also in said tubular portion an opening adapted to register with such an outlet of the overflow-passage. 90
